DESIGN FOR A SMOKING PIPE ATTACHMENT

Lewis W. Russi, Denver, Colo.

Application September 20, 1946, Serial No. 133,442

Term of patent 3½ years

(Cl. D85—8)

To all whom it may concern:

Be it known that I, Lewis W. Russi, a citizen of the United States, residing in the city and county of Denver, and State of Colorado, have invented a new, original, and ornamental Design for a Smoking Pipe Attachment, of which the following is a specification, reference being had to the accompanying drawing, forming part thereof.

In the drawing:

I claim:

The ornamental design for a smoking pipe attachment, as shown.

LEWIS W. RUSSI.
